MEANS FOR APPLYING A TRIMMING CONDENSER TO A MAIN CONDENSER

Albion D. T. Libby, East Orange, N. J., assignor to Condenser Development Corporation, Newark, N. J.

Application July 30, 1932, Serial No. 626,452

3 Claims. (Cl. 175—41.5)

This invention relates to improvements in the design of variable electrical condensers such as used in radio receiving sets.

In the design of gang condensers, it is the usual practice to provide each condenser unit with what is known in the trade as a trimmer. This trimmer condenser ordinarily consists of a single plate mounted so as to function in parallel with its associated main condenser unit, whereby the initial capacity of the main condenser may be slightly varied by adjustment of the trimmer plate.

It is also quite the usual practice to provide the main condenser units with some compensating means whereby the capacity curve of the condenser may be automatically varied over its range in order that the various tunable circuits may be brought as near alike as possible to the maximum tuning point at various settings of the tuning dial. Various other features are sometimes specified by the receiving set manufacturers so that the condenser manufacturer must be in position to furnish condensers that will meet all the various requirements which may or may not include the trimmer condenser.

If the gang condenser can be built and placed in stock without the trimmer condenser, but arranged so that the same may be readily added without changing the adjustment of the various units of the gang, much time and expense can be saved when an order is received requiring a trimmer plate.

My invention is directed to means for quickly attaching the trimmer condenser without disturbing the normal calibration of the main condenser with which it is associated, so that if the condenser manufacturer, on receipt of an order, has condensers in stock without the trimmer, and a trimmer is required, the same may be quickly added; or if the condensers in stock have trimmers thereon and the order calls for tuning condensers without trimmers, these trimmer plates may be quickly removed without disturbing the adjustments that have already been made on the main condenser.

Another object of my invention is to provide means for mounting a trimmer condenser which is applicable to a gang condenser of the compact type; that is to say, one in which the condenser units are small or compressed in dimensions, as well as one where the mounting space is not limited.

My improvement is shown in the annexed drawing, in connection with a two-gang condenser, but it is to be understood that any number of con-

denser units may be included in the gang. In the drawing:

Figure 1 illustrates a side elevation of a two-gang condenser in which the groups of rotor plates are in partial engagement with their respective stator plates, one of the units of the gang being equipped with a trimmer plate, while on the other unit the trimmer plate has been removed to show certain details.

Figure 2 is a fragmentary sectional view on the 10 line 2—2 of Figure 1.

Figure 3 is a view on an enlarged scale of the preferred form of means for mounting the main and trimmer condensers.

In the drawing, 1 is a frame having end-support plates 2 and 3 carrying an operating shaft 4 supported preferably on anti-friction bearing members carried in the races 5 and 6, all as shown and described in Cramer Patent 1,800,719, issued April 14, 1931. The shaft 4 carries sleeves 7 and 8 to which the rotor groups of plates 9 and 10 are attached in any satisfactory manner. As illustrated, the outer ends of the rotor plates 9 are fastened together by tie-plate 11, while the outer ends of the groups of rotor plates 10 are fastened together by tie-plate 12.

The side members of the frame 1 have openings 13 and 14 therein with upturned lugs 15 and 16 projecting a short distance into these openings. Fastened to the lugs 15 and 16 in any satisfactory manner, as by rivets 17, are insulators 18. To the other ends of the insulators 18 are attached the stator group of plates 19. The plates 19 are provided with notches or recesses 20 over which a tie-bar 21 is positioned, and to which 35 tie-bar the plates 19 are fastened in any satisfactory manner.

Within the recess 20, is positioned a screw-plate 22 into which screws 23 are screwed, thereby clamping the stator plates firmly to the insulators 18, it being understood that there is at least a pair of these insulators, one on each side of the condenser frame for each main condenser. Each screw 23, while having an external thread 24, is also provided with an internal thread 25. The 40 internal thread 25 is adapted to receive an auxiliary fastening means or screw 26 which latter screw is adapted to mount the trimmer condenser plate 27 on the insulator 18. It will be seen from Figures 2 and 3 that the trimmer plate will be 50 clamped by the auxiliary screws 26 against the heads 28, to the main fastening means or screws 23. The trimmer condenser plate 27 overlaps the frame 1 as shown in Figures 1 and 2, and is kept from electrical contact therewith by an insulator 55

29, and adjusted with respect thereto by means of an adjusting screw 30 insulated from the trimmer plate 27 by an insulator 31. The lower end of the trimmer plate 27 ends in a terminal 32 to which electrical connections may be made. Electrical connection to each stator may be made by means of a small clip permanently fastened under the head 28 of the screw 24; or as is sometimes done, it may be made by the clip being mounted under 10 the heads of the corresponding standard screws on the opposite side of the condenser in the usual manner.

From what has been said, it will be readily understood that the main fasteners or screws 23 15 which are used for mounting the main condenser as explained, are much heavier than the screws 26, and when the main fastening screws 23 are set up, the main condenser is rigidly held in place. Since the auxiliary screws 26 are independent 20 of the main mounting screws 23, it will be seen that the trimmer plate may be put on or taken off without in any way disturbing the main mounting screws or the setting of the main condenser, and no additional mounting means are 25 required on the insulators 18.

Having thus described my invention, what I claim is:

1. For an electrical condenser having a frame and relatively movable sets of elements carried 30 thereon and also having means for attaching one set of said elements to at least two insulators car-

ried by the frame, said attachment means including members going through the insulators; a trimmer condenser plate adapted to be quickly mounted on the insulator by means directly engaging said attachment members but without disturbing the same, and means for adjusting the capacity position of said trimmer plate with respect to the frame.

2. For an electrical condenser having a frame and relatively movable sets of elements carried 10 thereon and also having means for attaching one set of said elements to at least two insulators carried by the frame, said attachment means including members going through the insulators; a trimmer condenser plate adapted to be quickly 15 mounted on the insulator by means of independently operated screws going directly into certain of said attachment members, and means for adjusting the capacity position of said trimmer plate with respect to the frame.

3. Means for mounting a trimmer condenser plate in operative relation to a main condenser and its supporting frame, said means including screws for assisting in fastening the main condenser to the frame, at least a part of said screws 25 having an internal thread as well as an external thread, and auxiliary screws threaded into the internal threads of said first-mentioned screws for holding the trimmer plate against the heads of said first-mentioned screws.
